UNITED STATES PATENT OFFICE

RALPH D. MERSHON, OF NEW YORK, N. Y.

ELECTROLYTIC CONDENSER

Application filed November 9, 1929. Serial No. 405,872.

In electrolytic condensers having a plurality of anodes immersed in an electrolyte and connected in parallel inside the condenser, the practice heretofore has been to weld the 5 anodes to busbars. It is important that the welded joints be perfect since crevices left by imperfect welding may permit lodgment of gas bubbles therein with consequent corrosion of the metal. However, adequate welding 10 of filming metal, as for example aluminum, required considerable skill and care, and the use of a flux is prohibited because of the practical certainty of contamination of the electrolyte by the fluxing agent or agents. 15 Moreover, in a condenser having groups of anodes the anodes of one group are "interleaved" with those of the other. If there are two groups of two anodes each, the anodes of each group may be made by bending a sheet 20 of metal to U-shape, after which the two groups or pairs can be interleaved in the manner suggested by the symbol conventionally used to represent a condenser in electrical diagrams; but with three or more in a group this 25 method is manifestly impossible.

I have accordingly been led to devise my present invention, which has for its chief object to provide an assembly of interleaved anodes in which the anodes of each group are 30 integral with each other and in which the assembly is open between the anodes at the side, top and bottom edges thereof to permit free and unimpeded circulation of the electrolyte. Another object is to provide a simple and convenient method of making anode 35 assemblies of the type indicated. To these and other ends the invention comprises the novel features hereinafter described.

One form of the invention is illustrated in 40 the accompanying drawings, in which:

Fig. 1 shows a strip of sheet aluminum or other filming metal shaped and cut to constitute a blank for making an anode assembly or group having four anodes.

Fig. 2 shows in perspective a blank such as shown in Fig. 1, bent to form and ready to be interleaved with another similar group.

Fig. 3 shows in perspective two anode groups as interleaved for use.

Fig. 4 shows a blank such as shown in

Fig. 1, provided with stiffening ribs around the edges of the anode sections, and with corrugations inside of the ribs to increase the surface area.

Fig. 5 is a cross section on line 5—5 of Fig. 4.

Fig. 6 is a cross section of an electrolytic condenser having anodes constructed in accordance with my present invention. Any suitable means, not shown, can be employed 60 to support the anodes and space the same apart, as for example a rack such as described in the prior patent of John S. Ridgile and myself, No. 1,285,305, issued November 19, 1918.

In making my improved anode assembly in the preferred way I take a rectangular piece of sheet metal, as 10, Fig. 1, and cut equidistant transverse slits 11 extending from one of the longer edges, say the lower edge 12, but terminating short of the other edge, and at these ends short slits 13 are cut, extending equidistantly on either side of the long slits, forming T-shaped slits. I may also cut notches 14 in the lower edge, for the purpose stated below.

The blank described can now be bent at right angles back and forth along the vertical dotted lines at the ends of the T-heads 13, to the form shown in Fig. 2, giving four 80 parallel plates or anodes, 16, 17, 18, 19, connected to each other by integral strips 20, 21, 22, at alternate side edges, with such side edges or edge portions extending beyond the strips. That is, the connecting strips are set 85 in or back from the adjacent side edges.

Two such assemblies can be readily interleaved by inverting one and inserting the other down into it, as illustrated in Fig. 3. In this figure the anodes of the inverted 90 group are designated 16a, 17a, 18a, 19a. The notches or recesses 14 receive the strips 13, allowing the same to pass the notched plates or anodes without making contact therewith. In this way the bottom edges of the anodes 95 can be arranged flush with each other in the same horizontal plane, and so also the top edges. If the flush arrangement is not desired the recesses may be omitted. In either case the entire assembly is open at the side, 100

top and bottom edges of the anodes, thus permitting the electrolyte in which the anodes are immersed to circulate freely throughout all parts of the anode assembly. This is a highly advantageous feature as it gives convection currents full play and thereby facilitates dislodgment of bubbles of gas formed at the surface of the plates. Such bubbles clinging to the plates invariably cause corrosion of the metal and serious injury to the plates results unless the bubbles are removed.

It will of course be understood that the invention is not limited to four anodes, but that as many may be provided as will give the capacity desired.

The anodes may be stiffened by an embossed rib around the edges, as at 23, Figs. 4 and 5, and the connector strip 20 may have a rib 24. To increase the surface area of the plates they may be corrugated, as indicated at 25a. The ribs and corrugations can be conveniently formed by die-pressing, as will be readily understood.

A condenser having anode assemblies of the type described above is illustrated in Fig. 6, having anodes 16, 16a, 17, 17a, 18, 18a, 19, 19a, immersed in an electrolyte 25 contained in a tank or vessel 26. The terminals 27, 28, for connection with an alternating current circuit, may be welded to the appropriate anodes, or they may be integral therewith, as will be readily understood. The condenser is excited by any suitable source of unidirectional voltage and current, as for example a D. C. generator 29, having its positive pole connected to the midpoint of a choke coil 30 which spans the condenser terminals 27, 28. The negative pole of the exciting source is connected to a non-filming cathode 31 immersed in the electrolyte. By this means the anodes may have impressed upon them a positive potential or bias sufficient to prevent any flow of current from the electrolyte through the films to the metal of the anodes. The anodes may be of the ribbed or corrugated type illustrated in Figs. 4 and 5 but they are not so shown in Fig. 6 to avoid unnecessary complication. For the same reason I do not show a cover for the tank or a supporting rack for the anodes.

It is to be understood that the invention is not limited to the form herein specifically illustrated but can be embodied in other forms without departure from its spirit. It is also to be understood that the invention can be used to advantage in other electrolytic apparatus, as for example lightning arresters and rectifiers.

I claim—

1. An anode assembly for electrolytic condensers, comprising a group of plates of filming metal arranged side by side and connected at the top at alternate side edges by strips of the same metal, integral with the plates and set back from the adjacent side edges

thereof, and a like group with its integral connecting strips at the bottom, the two groups being interleaved by insertion of one into the other.

2. An anode assembly for electrolytic condensers, comprising a group of plates of filming metal arranged side by side and connected at their top edges at alternate side edges by strips of the same metal integral with the plates and set back from the adjacent side edges, the bottom edges of a plurality of the plates being notched to receive the connecting strips of a similar assembly when the two are interleaved in the manner described.

3. An electrolytic condenser comprising an electrolyte and anode groups immersed therein, each group being composed of a plurality of anode plates, the plates being interleaved and those of each group being integrally connected at alternate side edges by strips of the anode metal set back from the adjacent edges, the connecting strips of one group being at the top and those of the other being at the bottom.

4. An electrolytic condenser as described in claim 3, in which appropriate anode plates of each group are provided with recesses to receive the connecting strips of the other without making electrical contact therewith.

5. An electrolytic condenser comprising an electrolyte and groups of anodes immersed therein, each group being composed of at least three anodes arranged side by side, the anodes of each group being connected with each other by integral strips of a single thickness of metal and the groups being interleaved with the anodes of one group alternating with those of another, and the groups being open between the anodes thereof at their top and bottom and both side edges, whereby the electrolyte has unrestricted access to all surfaces of the anodes and unimpeded circulation of the electrolyte is permitted through all parts of the assembly.

In testimony whereof I hereto affix my signature.

RALPH D. MERSHON.
